DESIGN FOR A COMBINED MUFF AND HANDBAG OR SIMILAR ARTICLE

Morris Wolf, New York, N. Y.

Application March 8, 1944, Serial No. 112,824

Term of patent 7 years

(Cl. D87—3)

To all whom it may concern:

Be it known that I, Morris Wolf, a citizen of the United States of America, residing in New York city, county of New York, and State of New York, have invented a new, original, and ornamental Design for a Combined Muff and Handbag or Similar Article, of which the following is a specification, reference being had to the accompanying drawing, forming part thereof, wherein,

Figure 1 is a front elevational view of a combined muff and handbag or similar article showing my new design.

Figure 2 is an end elevational view, and Figure 3 is a fragmentary open top view thereof with a portion of the handles omitted for convenience of illustration.

The rear of the article is substantially like the front shown, except that the flower ornamentation is omitted.

I claim:

The ornamental design for a combined muff and handbag or similar article, substantially as shown and described.

MORRIS WOLF.
